UNITED STATES PATENT OFFICE.

JAMES CLARK, OF BRADFORD, PENNSYLVANIA, ASSIGNOR TO S. R. DRESSER MANUFACTURING COMPANY, OF BRADFORD, PENNSYLVANIA, A CORPORATION OF PENNSYLVANIA.

CLAMPING-RING FOR PIPE-COUPINGS AND PROCESS OF MAKING SAME.

1,287,884.

Specification of Letters Patent. Patented Dec. 17, 1918.

Application filed July 6, 1918. Serial No. 243,729.

To all whom it may concern:

Be it known that I, JAMES CLARK, a citizen of the United States, residing at Bradford, in the county of McKean and State of Pennsylvania, have invented certain new and useful Improvements in Clamping-Rings for Pipe-Couplings and Processes of Making Same; and I do hereby declare the following to be a full, clear, and exact description of the invention, such as will enable others skilled in the art to which it appertains to make and use the same.

My invention consists in the novel features hereinafter described, reference being had to the accompanying drawings which illustrate one form in which I have contemplated embodying my invention, and one form of mechanism by which it may be carried into effect, and the said invention is fully disclosed in the following description and claims.

The object of my invention is to provide a clamping ring for pipe couplings of the kind generally termed rubber packed pipe couplings, which is adapted especially for smaller sizes of pipe, formed of wrought metal such as wrought iron or steel, and so constructed as to provide great strength and durability and capable of being very cheaply manufactured, and my invention also includes the improved method of manufacturing these clamping rings commercially.

My improved clamping ring hereinafter described, and illustrated in the accompanying drawing, is an improvement on the clamping ring set forth in my former patent of the United States #849,371, dated April 9, 1907. In the accompanying drawings,

Figure 1 represents a perspective view of my improved clamping ring.

Fig. 2 is a top plan view of the same.

Fig. 3 is a side elevation of the same.

Fig. 4 is a central longitudinal section of the ring.

Fig. 5 is a section on the line 5—5 of Fig. 2.

Fig. 6 is a perspective view of the blank from which the ring is formed.

Fig. 7 is a sectional view of the die pressing mechanism, by which the ring is produced, showing the blank in position ready to be pressed.

Fig. 8 is a similar view showing the posi-

tion of the parts after the completion of the pressing operation.

The production of a clamping ring of the kind described herein, of wrought metal formed in one piece, has long been desired, but no means has been found heretofore whereby it could be commercially produced. In my former patent above alluded to, I have shown a clamping ring having some of the general characteristics of my present clamping ring, but formed in two parts requiring separate operations for the production of each and necessitating that the parts be assembled and preferably welded or brazed together, as otherwise the separate parts are apt to become disassociated in shipping and handling the clamping rings and result in delay and loss of valuable time in assembling and using the device.

A clamping ring of the kind herein shown is intended for use in connection with the well known type of "Dresser" pipe coupling and among the essentials of construction may be mentioned the following. A concentrically located circular pipe aperture which should be preferably true and fit as closely to the pipe as possible, allowing the smallest possible margin for the inevitable variations in the exterior surfaces of the pipe; an annular packing recess surrounding the pipe aperture to receive a rubber or other packing ring, a plate portion provided with bolt holes disposed laterally of the packing recess and having sufficient strength after the formation of the bolt holes to withstand the great pressure exerted by the bolt which produces a compression of the rubber or other packing ring and forces it against an annular middle ring or equivalent sleeve portion of the coupling and against the exterior surface of the pipe with such pressure as to make gas-tight joints capable of sustaining great internal pressure at all times, while permitting longitudinal movement of the pipe with respect to the coupling to accommodate the expansion and contraction of the pipes due to changes in atmospheric conditions.

I will first describe the construction of my improved clamping ring which is illustrated in Figs. 1 to 5 inclusive of the accompanying drawings. This ring comprises a plate member 1 preferably of oval shape,

which is provided with a centrally, truly circular pipe aperture 2, and with bolt holes 3—3 disposed at equal distances from the center of the pipe aperture. Integrally 5 with the plate member 1 and surrounding the pipe aperture 2 is a circular flange 4, projecting from one face of the plate member and forming a circular wall, the diameter of the circle being greater than that of the pipe aperture, thus forming an annular 10 packing recess to surround the pipe when the latter is placed in engagement with the pipe aperture 2. In Fig. 4 I have indicated the position of the pipe in dotted lines and 15 have also indicated this packing recess, at 5.

The formation of the bolt holes 3 and pipe aperture 2 necessarily remove large quantities of the metal from the plate member 1 and in order to strengthen the structure and 20 prevent the buckling of the plate member and flange 4, the plate member is provided with a marginal flange 6 which is formed integral with the annular flange 4, and projects from the plate member on the same side 25 as the flange 4. This construction in itself imparts great strength to the plate member 1, and also to the flange 4, which it will be understood is also integral with the plate member 1, thus uniting the elemental parts 30 of the coupling in an integrally braced structure so that the bolt strain and the strain on the packing recess is distributed and equalized through the integral connection between the reinforcing flange 6, and the plate member 1, and flange 4.

It is not necessary to have the flange 6 of as great height as the flange 4 of the packing recess, and I therefore prefer to have the portions of the flange 6 at each end of the 40 plate member 1 of less height than the flange 4 and to provide inclined shoulders, indicated at 6^a, at the four points where the flange 6 merges into and unites with the flange 4, on opposite sides of the clamping ring. In order to further reinforce the ring, I prefer to form the flange 4 of greater width 45 adjacent to the plate member than at its outer edge and to have it merge into the plate member in a curved shoulder on the outer and inner side of the flange, as indicated at 4^a and 4^b, see Fig. 4, and likewise merge the inner face of the flange 6 into the plate member by curved shoulder 6^b, making this flange also heavier adjacent to the plate 50 member than at its outer face. These curved shoulders 4^a, 4^b, 6^b, provide fillets of metal integral with the plate member and with the respective flanges which brace and stiffen the entire structure without adding undue 55 weight.

In order to still further stiffen and strengthen the structure adjacent to the points where it would be most likely to buckle, namely at the points where the flange 6^a unites with the flange 4, I provide inclined

shoulders 6^c, one of which is shown in detail in Fig. 5, which is a section on the line 5—5 of Fig. 2, the increased metal in this shoulder forming an integral brace uniting the plate member 1 and the flange members 70 4 and 6, and increasing the stiffness and resistance of the entire ring structure.

The improved ring shown in Figs. 1 to 5 inclusive, is formed by a hot compressing operation from a blank illustrated in Fig. 6 75 which is of greater thickness than the plate member 1 of the finished ring, but of less thickness than the height of flanges 4 and 6, and particularly of the flange 4. In the production of this improved clamping ring I 80 employ two operations. The first operation is a hot compression between dies and in Figs. 7 and 8 I have illustrated one form of die which is suitable for carrying out this compression step. In these figures 10 represents the female die which is provided with a central aperture of oval form to receive the blank illustrated at A in Fig. 6, said female member being provided with the usual stripper 11. 12 represents the male 85 die which is provided with projecting portions 13, 14, 15 and recesses 16, 17. The projections 14 is of circular shape of the size of the circle within the flange 4; the projections 13 and 15 are of the size and form of the 90 recesses at each end of the finished ring between the flanges 4 and 6; the recesses 16 and 17 of the die are of the form of the flanges 4 and 6 thereof and are so constructed as to produce the curved or inclined shoulders 4^a, 4^b, 6^a, 6^b, and 6^c hereinbefore described.

The blank A is punched, stamped, or otherwise formed of sheet metal preferably steel or wrought iron of the size and shape of the periphery of the clamping ring to be made and of the proper thickness to provide sufficient metal to completely fill the recesses between the die members 10 and 11 and 12, when the upper die is forced to its final position. The blank is heated to a softening temperature and placed on the stripper 11 within the die member 10, as shown in Fig. 7, and the forming die 12 is then forced downwardly by hydraulic pressure (or other suitable power), squeezing the blank with sufficient pressure to cause the metal to flow and fill the recesses in the forming die 12, as shown in Fig. 8 in which arrows illustrate, although inadequately, the manner in which the displaced metal of the blank flows upward into the recess portions 16 and 17 of the die so as to produce the flanges 4 and 6 and produce the form of the clamping ring which will be of greater thickness from the outer face of the plate member to the outer face of the flange 4, and preferably from the outer face of the flange member to the outer face of the flange 6, than the thickness of the original blank.

The ring thus formed is then removed from the die by the stripper 11 and operated upon by suitable punching mechanism by means of which the pipe aperture 2 is formed so that it is truly circular and exactly concentric with the inner wall of the flange 4, the bolt holes 3 being also punched preferably at the same operation at equal distances on opposite sides of the center of the pipe aperture. If the pipe aperture is not formed truly circular, a much greater allowance or clearance must be allowed between the inner edge of the pipe aperture and the pipe, as it is necessary to allow for any inequalities both in the pipe aperture and in the pipe. By making the aperture truly circular, a very minute allowance is all that is necessary, and only for the usual inequalities in the exterior surface of the pipe. This secures a fairly tight fit of the pipe aperture around the pipe and prevents the possibility of the inner portions of the rubber or other gasket being crowded through the space between the pipe aperture and the pipe, which might otherwise occur. The formation of the bolt apertures in this exact and accurate manner also results in producing a ring which is equally stiff and strong to withstand strain on each side of the pipe so that there is no danger of the strength of the clamping ring being impaired on one or both sides by an unequal spacing of the bolt holes, which would result in disturbing the correct distribution of the bolt strain and the strain on the packing recess as hereinbefore described. It is obvious that this clamping ring can be very economically produced on a commercial scale and it can also be made from scrap material, and thus effect still greater economy of manufacture.

What I claim and desire to secure by Letters Patent is:—

1. A clamping ring for pipe couplings formed of wrought metal in one piece and comprising a plate member having a central aperture, bolt holes exterior thereto, an annular flange member concentric with and surrounding the central pipe aperture projecting from one face of and formed integral with the plate member, said plate member being also provided on the same face as the said flange with a marginal reinforcing flange integral with the plate member and having portions integral with and merging with said annular flange.

2. A clamping ring for pipe couplings formed of wrought metal in one piece and comprising a flanged plate member provided with a circular centrally located pipe aperture, and bolt holes located on opposite sides of the center of the pipe aperture, said plate member being provided with an annular flange surrounding and concentric with the pipe aperture, and formed integrally with

the plate member, and being also provided with a marginal reinforcing flange integral with the plate member and having portions merged into and integral with said annular flange, said flanges having curved shoulders adjacent to their union with the plate member to thicken the flanges and reinforce the structure of the ring at the points of union of said flanges with said plate member.

3. A clamping ring for pipe couplings formed of wrought metal in one piece and comprising a flanged plate member provided with a circular centrally located pipe aperture, and bolt holes located on opposite sides of the center of the pipe aperture, said plate member being provided with an annular flange surrounding and concentric with the pipe aperture, and formed integrally with the plate member, and being also provided with a marginal reinforcing flange integral with the plate member and having portions merged into and integral with said annular flange, inclined shoulders being formed inside of the marginal flange and exterior to the annular flange at their four points of intersection with each other and with the plate member by thickening the adjacent walls of said flanges to reinforce the ring structure.

4. A clamping ring for pipe couplings formed of wrought metal in one piece and comprising a flanged plate member provided with a circular centrally located pipe aperture, and bolt holes located on opposite sides of the center of the pipe aperture, said plate member being provided with an annular flange surrounding and concentric with the pipe aperture, and formed integrally with the plate member, and being also provided with a marginal reinforcing flange integral with the plate member and having portions merged into and integral with said annular flange, said flanges having curved shoulders adjacent to their union with the plate member to thicken the flanges and reinforce the structure of the ring at the points of union of said flanges with said plate member, throughout the extent of said flanges, and said ring having inclined shoulders formed inside of the marginal flange and exterior to the annular flange at their four points of intersection with each other and with the plate member, to additionally reinforce and stiffen the structure of the ring.

5. The herein described process of forming an integral wrought metal clamping ring for pipe couplings having a flat plate member, a centrally disposed annular flange on one face thereof, and a marginal flange integral with said plate member and said annular flange, which consists in forming a blank of wrought sheet metal having the peripheral form of the completed ring and being of less thickness than the height of

4
one or both of said flanges, heating said blank to a temperature which will permit the metal to flow under pressure, and compressing said blank to displace central portions thereof and portions adjacent to each end within the marginal limits of the blank, and cause the displaced metal to flow in a direction away from the face of the blank around said central depression and adjacent to the marginal portions of the blank.

6. The herein described process of forming an integral wrought metal clamping ring for pipe couplings provided with a central truly circular pipe aperture, bolt holes exterior thereto, an annular flange surrounding the pipe aperture, and a marginal flange integral with the plate member

and said annular flange, which consists in forming a substantially oval blank from wrought sheet metal, having the exterior peripheral form of the finished ring, heating said blank to a temperature which will permit the metal to flow under compression, compressing the metal to displace the centrally located portions on one face, and portions adjacent to each end of the blank, and causing the displaced metal to flow in a direction away from the face of the blank to produce said flanges, and punching the pipe aperture and said bolt holes through the depressed portions of the blank.

In testimony whereof I affix my signature.

JAMES CLARK.
